ATTEST.

UNITED STATES PATENT OFFICE.

JOHN H. McGOWAN, OF CINCINNATI, OHIO.

DESIGN FOR A STEAM-PUMP PISTON.

Specification forming part of Design No. 5,049, dated June 27, 1871.

To all whom it may concern:

Be it known that I, JOHN H. McGOWAN, of Cincinnati, Hamilton county, Ohio, have invented and produced a new and original Design for a Steam-Pump Piston, of which the following is a specification:

The nature of my design is fully represented in the accompanying illustration, to which reference is made.

I claim as my invention—
The design for a steam-pump piston, as shown.
In testimony of which invention I hereunto set my hand.

JOHN H. McGOWAN.

Witnesses:

GEO. H. KNIGHT,
JAMES H. LAYMAN.
